UNITED STATES PATENT OFFICE.

NIELS PETER HESKIER, OF COPENHAGEN, DENMARK.

DESIGN FOR A GALVANIC PILE.

SPECIFICATION forming part of Design No. 22,954, dated December 5, 1893.

Application filed September 12, 1892. Serial No. 445,707. Term of patent 7 years.

To all whom it may concern:

Be it known that I, NIELS PETER HESKIER, a subject of the King of Denmark, residing at Copenhagen, Denmark, have invented and 5 produced a new and original Design for a Galvanic Pile, of which the following is a specification.

In the accompanying drawing the figure illustrates a perspective view of the design. 10 The leading feature of the design is the configuration of the arms and the ornamentation of the surface. The article is made with four arms or branches having rounded cor-

ners and narrowing in toward the center. The surface contains lines radiating from the center along the center of each of the arms. 15

I claim—

The design for a galvanic pile herein shown and described.

In witness whereof I have hereunto set my 20 hand in presence of two witnesses.

NIELS PETER HESKIER.

Witnesses:

S. STEINBERG,
H. HESKIER.
